DESIGN FOR A BROOM COVER

James Cavallo, Fairview, N. J.

Application September 2, 1938, Serial No. 79,725

Term of patent 3½ years

To all whom it may concern:

Be it known that I, James Cavallo, a citizen of the United States, residing at Fairview, county of Bergen, and State of New Jersey, have invented a new, original, and ornamental Design for a Broom Cover, of which the following is a specification, reference being had to the accompanying drawing, forming part thereof.

I claim:

The ornamental design for a broom cover, substantially as shown.

JAMES CAVALLO.
